MILK BOTTLE CASE

Filed Oct. 10, 1923

Fig. 3.

UNITED STATES PATENT OFFICE.

JAMES EDWIN BOWEN, OF SAN FRANCISCO, CALIFORNIA.

MILK-BOTTLE CASE.

Application filed October 10, 1923. Serial No. 667,734.

To all whom it may concern:

Be it known that I, JAMES E. BOWEN, a citizen of the United States, residing in the city and county of San Francisco, and State of California, have invented a new and useful Improvement in a Milk-Bottle Case, of which the following is a specification.

My invention relates to improvements in milk bottle cases of the type wherein wooden sides and ends are used to form a case with an open bottom.

In the present state of the art the wooden milk bottle cases, comprising sides and ends connected together to form an open bottom case, has been found most practical for sanitary and other purposes.

Within the case bottle supporting elements are provided to retain both empty and full milk bottles in spaced relation. The open bottom provides accessibility for washing purposes. In this type of case, however, it has been found that the bottoms of the cases, due to dragging along concrete floors and the like, wear and frequently splinter.

The ends of the case are provided with handle apertures and the weight of the full bottles is thus borne by the end pieces when said case is lifted, and this weight frequently causes said end pieces to split. Frequent washing of the wooden cases, and their consequent immersion in strong detergents, will also cause the sides and ends of the case to split and also to cause said ends and sides to separate.

I propose to provide an improved open bottom milk case comprising wooden sides and ends having improved means for easily and inexpensively retaining or holding said pieces together as well as for preventing wear on the bottom edges of the wooden case when dragged over concrete floors and the like, and also to facilitate stacking of said cases.

A further object of the present invention is to provide improved means for tightly and rigidly connecting the sides and ends of the case and for permanently holding them together.

I accomplish these and other objects by means of the device disclosed in the drawings forming a part of the present specification wherein like characters of reference are used to designate similar parts through-

out the said specification and drawings, and in which—

Fig. 1 is a broken side elevation of my improved milk bottle case;

Fig. 2 is a plan view thereof;

Fig. 3 is an end elevation of Fig. 1;

Fig. 4 is a transverse sectional view of the case; and

Fig. 5 is an enlarged broken sectional view disclosing the manner in which the inner straps are fastened to the bottom angle and to the side pieces.

Referring to the drawings the numeral 1 is used to designate the sides and 2 the ends of a wooden milk bottle case having an open bottom. The ends are provided with hand-holes 3 which serve as handles when lifting the bottle cases. The usual stacking members 4 are arranged to project above the upper edges of the ends 2 to align, and retain alignment of the cases when stacked.

When passing through the various washing and bottle filling machines and when being pulled about the concrete floors of the creamery or dairy, the wooden cases are exposed to considerable wear and the strong detergents used to clean the cases also adds to the sometimes rapid disintegration of the cases. In order to further strengthen these open bottomed wooden milk bottle cases I have provided a rectangular angle iron 6 which is fastened around the lower edges of the ends and sides 2 and 1 respectively. This angle iron frame 6 not only holds the sides 1 and ends 2 rigidly and permanently together at their corners but also protects the comparatively soft wooden edges from wear as the bottle case is dragged over the concrete floors usually found in creameries.

In order to further strengthen the case I have provided the inverted U-shaped members or angle irons 7 which cover the ends of the sides 1 and the top of the ends 2 thereby further securing against separation the adjoining edges of said sides 1 and ends 2 of the case.

The open or lower ends of the members 7 are riveted to the corners of the rectangular frame 6 said elements 6 and 7 thereby constituting a tray and handles for the support and retention of the wooden case constituted by the sides 1 and ends 2.

In other words, the angle irons 7 serve to not only rigidly hold and retain the adjoining corners of the sides and ends together

but also to rigidly hold said sides 1 and ends 2 upon the frame 6 thereby providing a rigid unit.

5 The angle irons 7 serve the further purpose of holding the severed parts of the ends 2 together when they become split.

In order to further assist in retaining together split portions of a split end piece 2 I have provided the vertically disposed straps 8 which are riveted at their lower ends to the rectangular frame 6 and to the side pieces 1 at points intermediate the ends of said straps 8. These straps are preferably mounted upon the outer surface of the ends 2.

Similar straps 9 are mounted upon the insides of the sides 1, their lower ends being secured to the rectangular frame 6 by means of suitable rivets 11 as disclosed in Fig. 5 of the drawings, said rivets 11 passing through the said sides 1 adjacent the lower edges thereof. By means of this novel arrangement the sides 1 are securely and rigidly fastened to the rectangular frame 6.

25 By means of my improvement hereinabove described it is obvious that the wooden cases now in use may not only be strengthened but also may be protected from excessive wear and held rigidly together in the event that 30 they become split and the period of utility of said case is materially lengthened.

The various means for holding the milk bottles in spaced relation within the case are shown at 12 but as they are well known in 35 the art and form no part of the present invention it is not necessary to describe them.

Having thus described my invention what I claim as new and desire to secure by Letters Patent is—

40 1. The combination with a milk bottle case comprising wooden sides and ends and having an open bottom, of an angle iron band mounted upon the lower edges of said sides and ends to prevent wear and to hold 45 said sides and ends together; and inverted U-shaped angle irons mounted around the

ends of said case and secured to the angle iron band to hold said sides and ends to said band; and metal straps secured to said angle iron band and to the sides and ends at intermediate points to prevent splitting of 50 said sides and ends.

2. The combination with a milk bottle case comprising wooden sides and ends and having an open bottom, of a rectangular angle iron frame mounted upon the lower edges of said sides and ends to prevent undue wear and to rigidly hold said sides and ends together; and inverted U-shaped angle iron members arranged around the top and side corners of the ends of said milk bottle case, and having their ends connected to the rectangular angle iron frame to rigidly hold 55 said sides and ends onto said frame; and straps arranged intermediate the ends of the sides and ends of the case and connected to said sides and ends and to the rectangular frame.

3. The combination with a milk bottle case comprising wooden sides and ends and having an open bottom, of a rectangular angle iron frame mounted upon the lower edges of said sides and ends to prevent undue wear and to rigidly hold said sides and ends together; and inverted U-shaped angle 70 iron members arranged around the top and side corners of the ends of said milk bottle case, and having their ends connected to the rectangular angle iron frame to rigidly hold 75 said sides and ends onto said frame; and straps arranged on the outside surfaces of said ends, said straps being connected at their lower ends with the rectangular frame; and similar straps arranged on the inside surfaces of the sides and connected at their 80 lower ends to said rectangular frame and through the said sides, to hold the same rigidly onto said frame.

In witness whereof I hereunto set my signature.

JAMES EDWIN BOWEN.
